UNITED STATES PATENT OFFICE.

H. CLAY BASCOM AND CYRUS A. HODGES, OF TROY, NEW YORK, ASSIGNEES
TO SAID BASCOM.

DESIGN FOR A PARLOR-STOVE.

SPECIFICATION forming part of Design No. 15,398, dated September 16, 1884.

Application filed June 17, 1884. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Parlor-Stoves, of which the following is a specification, reference being had to the accompanying cut, print, or engraving of a stove having said design.

This design embraces several new and distinct parts and combinations of parts which go to make up the whole design, as shown in the accompanying illustration, and hereinafter specified.

One distinguishing feature of this design is the configuration and ornamentation of the vase A, consisting of the convexly and concavely curved base part a, the cylindrical enlargement b, the central concavely curved upward extension, b', and the lateral curved parts c, having the lower ornaments, c', top ornaments, c'', and intermediate ornaments, c'''.

Another feature is the shape and ornamentation of the oval cover, consisting of the upper concavely-curved portion, d, having the middle front open-work ornamentation, d', formed by united radial bars of angular and curved shapes, and the lateral radial open-work ornamentations d, and the lower convexly-curved portion, e, consisting of the peculiar open-work ornamentations represented.

Another feature is the shape and ornamentation of the front C, consisting of the upright plate g, curved convexly in the horizontal direction, and having on its upper portion the ornamentation D, consisting of the parts j k k' l, and having on its lower portion the box-form projection f, in which the upper part, h, has draft-apertures h', and the lower part, i, has illuminating-panes i'.

Another feature is the shape and ornamentation of the end door, E, consisting of the

compound ornament D' on the main curved part p, and the projecting lower panel, q. 45

Another feature is the shape and ornamentation of the legs, consisting of the curved portion r, having the ornaments s, downwardly-converging curved edge moldings t, straight top u, contracted part v, and the ribbed foot w. 50

The whole design embraces the shape and ornamentation of the vase A, cover B, the top under the cover, the front C, the end including the door E, and parts u v w, the bottom plate, and the legs. 55

We claim as new—

1. In a design for a stove, the shape and ornamentation of the vase A, consisting of the parts a b c c' c'' c''' as set forth. 60

2. In a design for a stove, the shape and ornamentation of the cover B, consisting of the open-work part d, d', d'', and e, as shown and described.

3. In a design for a stove, the shape and ornamentation of the front C, consisting of the parts g, D, and f, as described. 65

4. In a design for a stove, the shape and ornamentation of the end door, E, consisting of the parts D', p, and q, as shown and described.

5. In a design for a stove, the shape and ornamentation of the legs, consisting of the parts r s t u v w, as set forth. 70

6. A design for a stove, consisting of the vase A, cover B, the top below the cover, the front C, the end, the bottom plate, and the legs, shaped and ornamented as described and shown. 75

In testimony whereof we hereunto set our hands, in the presence of two subscribing witnesses, this 14th day of June, 1884.

H. CLAY BASCOM.
CYRUS A. HODGES.

Witnesses:

CHARLES H. BENEDICT,
CHESTER BASCOM.
